The screenshot shows the Lattice platform homepage. At the top, there is a navigation bar with links for Lattice, Platform, Solutions, Why Lattice, Resources, Pricing, Company, Sign in, and Request a demo. Below the navigation bar is a large call-to-action button with the text "BETTER TOGETHER" and a "Request a demo" button. The main headline is "Every tool you need to power strategic HR". A sub-headline below it says "See how Performance connects with the rest of the Lattice platform." To the right of the headline, there is a box titled "COLLABORATION & COLLABORATION" with the subtext "This person drives initiatives that enhance the productivity of our team and company." It shows two performance reviews for "Babina Puri (SELF)" and "Jonathan Castro (MANAGER)". The reviews are 5/5 and 4/5 respectively. Below this, there is a diagram showing the interconnectedness of various HR tools: Performance, Grow, Engagement, OKRs & Goals, Compensation, and Analytics. A plus sign (+) is placed between the Performance and Grow boxes. A callout box on the right side says "Run performance reviews to align employees on where they meet, exceed, or fall short of their roles' expectations." and "Learn more".
